fig.1

fig.2

fig.3

FIG. 1 is a front elevation view of a kite reel showing my new design in one embodiment wherein a side member has a scalloped or gear-like configuration in which the teeth of the gear are rounded and somewhat dome-like in appearance and wherein four of said dome-like teeth are shown.

FIG. 2 is a side elevation of FIG. 1 wherein all of the dome-like teeth are shown.

FIG. 3 is a front elevation of another embodiment wherein a side member of substantially the same character as shown in FIG. 1 is depicted without the scallops or gear-like configuration.

I claim:

The ornamental design for a kite reel, as shown and described.
